UNITED STATES PATENT OFFICE

JAMES H. DENNEDY, OF EVANSVILLE, INDIANA, ASSIGNOR, BY MESNE ASSIGNMENTS,
TO SERVEL, INC., OF NEW YORK, N. Y., A CORPORATION OF DELAWARE

REFRIGERATION

Application filed October 25, 1926. Serial No. 144,117.

My invention relates to refrigerators of the type employing motor, compression means, liquefaction means, and more particularly to the relation of various parts comprising a unit and still more particularly to the adaptation of air to refrigerant liquefaction.

In one form of my invention, a motor, a compressor and a condenser are mounted upon a common base and a plurality of fans are driven from the motor and so arranged that air is in part forced against the condenser and in part induced away from the condenser.

15 The invention includes various other phases of arrangement, construction, and operation which will be more fully hereinafter described and more particularly pointed out in the appended claims.

20 Referring to the accompanying drawings: Figure 1 is a front elevation view of a compressor machine unit shown as mounted in the lower part of a refrigerator cabinet, the refrigerator cabinet being shown in section; 25 Figure 2 is a top plan view of the unit shown in Figure 1; and Figure 3 is an end view of the same.

Referring more particularly to Figure 1, reference character 10 designates a base. At 30 each of four corners of the base is the support 11. On the forward part of the base are mounted a motor 12 and a compressor 13. Motor 12 has a shaft 14 and compressor 13 has a shaft 15 (Fig. 2). The motor and compressor are arranged so that shafts 14 and 15 extend parallel to each other. These shafts also extend transversally of the longitudinal dimension or extent of the base. Rearwardly of the compressor and motor lies a condenser 35 made up of a series of superimposed loops comprising straight sides and semi-circular ends. As can be seen from Figure 1, the condenser extends the full height of the unit and somewhat higher than the compressor. The loops of the condenser are held in proper place by means of supports 17. The condenser is long relative to its width, looking down upon the same, and may be said to extend transversally to shafts 14 and 15. The 40 condenser extends longitudinally the full

length of the base and has portions in line with both shaft 14 and shaft 15.

Reference character 18 represents a discharge connection for the compressor which is connected to one end of the condenser tubing as shown at 19 in Figure 3. The other end of the condenser is connected with a valve 20 which is normally open and is connected to a conduit 21 adapted to be connected to an evaporator which would preferably be situated in the upper part of the refrigerator cabinet. The return from the evaporator is connected to conduit 22 which connects with a member 23 comprising a switch control mechanism for cutting the 45 motor into and out of operation. The return fluid from the evaporator after passing through member 23 passes into conduit 24 and into the compressor through connection 50. The switch control mechanism is disclosed and claimed in my Patent No. 1,520,936, granted to me on December 30th, 1924, and inasmuch as it is not a part of the present invention, it is not herein further 55 described.

Electricity supplied to the motor causes rotation of shaft 14. This rotation is transmitted to shaft 15 by means of belt 27 which passes over pulleys 28 and 29 on shafts 14 and 15 respectively, the pulley 28 being of 60 considerably smaller diameter than pulley 29. Pulley 29 is the outer ring of a fan 30 which includes a series of blades 31. The motor operates to drive the belt 27 in the direction indicated by arrow 32 in Figure 2. 65 The blades 31 are so fashioned and arranged that rotation as thus indicated causes flow of air through the fan in the direction indicated by arrow 33 and on to the compressor. With respect to the condenser, this fan is 70 an induced draft fan and draws air across the condenser for the purpose of liquefying gaseous refrigerant introduced thereinto from the high pressure side of the compressor. The air passing through the fan 30 impinges upon the body of the compressor. Mounted upon shaft 14 is a fan 35 which has 75 its blades directed in opposite direction to that of blades 31. This fan is mounted rearwardly of belt 27, the diameter of pulley 28 80

85

90

95

100

being smaller than the external fan blade diameter. With the rotation above described, air passes through fan 35 in the direction indicated by arrow 36. As respects condenser 16 fan 35 is a forced draft fan.

Surrounding structure for the unit comprising the parts above described is provided with suitable openings 38 for admission and exhaustion of air.

10 While I have described in detail the preferred form of my invention, it is to be understood that this is not by way of limitation.

Having thus described my invention, what I claim is:

15 1. In a refrigerating apparatus, the combination of a base, a condenser formed of a flattened elongated coil disposed longitudinally of the base, a compressor and motor mounted in spaced relation on said base with parallel shafts disposed transversely of the base and substantially at right angles to the condenser, a fan on the motor shaft between the motor and condenser, a fan on the compressor shaft between the compressor and condenser, said fans being arranged to produce two currents of air moving in opposite directions through the condenser, and a single current of air over each the motor and the compressor.

30 2. In a refrigerating apparatus the combination of a base, an elongated condenser disposed longitudinally of the base, a compressor and motor mounted in spaced relation on said base with substantially parallel shafts disposed transversely of the base and substantially at right angles to the condenser, a fan driven from the motor, said fan being located between the motor and condenser, a fan driven by the compressor, said fan being located between the compressor and condenser, said fans being arranged to produce two currents of air moving in opposite directions through the condenser and a single current of air over each the motor and the compressor.

35 3. In a refrigerating apparatus the combination of a base, an elongated condenser disposed longitudinally of the base, a compressor and motor mounted in spaced relation on said base with substantially parallel shafts disposed transversely of the base and substantially at right angles to the condenser, a fan driven from the motor, said fan being located between the motor and condenser, a fan driven by the compressor, said fan being located between the compressor and condenser, said fans being arranged to produce two currents of air moving in opposite directions for cooling the condenser, the motor and the compressor.

In testimony whereof I affix my signature.
JAMES H. DENNEDY.
